CLAIM

The ornamental design for a vehicle tail table, as shown and described.

DESCRIPTION

FIG. 1 is a top perspective view of a vehicle tail table showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an enlarged view of a portion indicated with “9” in FIG. 2.

The broken lines illustrate portions of the vehicle tail table that form no part of the claimed design. The dot-dash broken lines in FIG. 2, and FIG. 9 are included to show a partially enlarged view only and form no part of the claimed design.
